UNITED STATES PATENT OFFICE.

ALLEN H. BEHR, OF BROOKLYN, NEW YORK.

TENNIS RACKET.

Application filed December 6, 1924. Serial No. 754,243.

To all whom it may concern:

Be it known that I, ALLEN H. BEHR, a citizen of the United States, and a resident of the borough of Brooklyn, county of 5 Kings, city and State of New York, have invented certain new and useful Improvements in Tennis Rackets, of which the following is a specification sufficient to enable those skilled in the art to which the invention appertains to utilize the same.

My improvements relate to formation of rackets, so called, used in the game of tennis; and more particularly to the cords used in the formation of the net work there- 15 of, and are designed to afford an intersticed woven contactual impact surface of superior elasticity and resilience, of exceptional strength and durability, and which is not affected by moisture or change in atmos- 20 pheric conditions, all as hereinafter fully set forth, the invention consisting in the specific construction, combination and arrangement of component parts described and claimed, and the distinctive feature be- 25 ing the use of a gut core strand covered with a textile weave and protected externally by a coating of waterproof varnish.

In the accompanying drawings I illustrate a practical embodiment of the essential features of my invention, although I do not restrict myself to the identical form and construction of parts shown herein by way of exemplification, since modifications in minor details, and equivalent mechanical 30 expedients may be resorted to with like results, and without departing from the spirit and intent of my invention in this respect.

With this understanding:—

Fig. 1, is a perspective view of a tennis racket made in accordance with my invention;

Fig. 2, a detail view on an enlarged scale illustrating the construction of the impact cord; and

Fig. 3, is a transverse section taken upon plane of line 3—3, Fig. 2.

The racket frame F, and its handle F', are of ordinary construction, the frame F, being formed with the usual perforations 50 f, f, for the threading and support of the cord C, constituting the impact medium for contacting with a tennis ball.

Said impact cord consists of a central strand or core c', of gut such as heretofore 55 used for the formation of the mesh of a

racket, around which is woven a covering c², of silk thread or equivalent textile material, the latter being in turn covered and surfaced with a coating of waterproof varnish c³, as indicated more particularly in 60 Figs. 2 and 3, of the drawing.

By this construction of impact cord C, the usual gut c', is reinforced and strengthened by the woven covering c², without impairing its flexibility, while the outer casing 65 of varnish renders the whole impervious to moisture, so that a relatively strong, tenacious, elastic resilient impact surface may be woven upon and within the frame F, not subject to deterioration by reason 70 of changes in atmospheric conditions, and of relatively long life and utility.

The silk or other textile fabric, covering and in direct contact with the gut core, acts as an absorbent medium and binder for 75 the external coating of waterproof varnish,—thereby effectually protecting the cord in a unitary sense, and maintaining and prolonging its efficiency.

In certain cases it may be desirable to 80 weave the silk-covered gut on the racket frame before the waterproof varnish is applied as a coating to said cord,—the application of the waterproof varnish to the cord thus in position as when applied to 85 the fabric covered gut in a preliminary stage. I do not however limit myself to the use of a waterproof varnish in this connection, since any varnish will act as a protective medium.

What I claim as my invention and desire 90 to secure by Letters Patent, is:—

1. A tennis racket having an impact medium consisting of a weave of cord comprising a core of gut, enclosed in a textile 95 covering coated with waterproof varnish, substantially in the manner and for the purpose set forth.

2. An impact medium for tennis rackets comprising a core of gut, enclosed in a textile covering coated with waterproof varnish, substantially in the manner and for the purpose set forth.

3. A tennis racket having an impact medium consisting of a weave of cord comprising a core of gut, enclosed in silk and covered with waterproof varnish, substantially in the manner and for the purpose set forth.

4. An impact medium for tennis rackets 110

comprising a core of gut enclosed in a weave of silk, substantially in the manner and for the purpose set forth.

5. An impact medium for tennis rackets comprising a core of gut enclosed in a weave of textile fabric, substantially in the manner and for the purpose set forth.
6. An impact medium for tennis rackets

comprising a core of gut enclosed in a weave of textile fabric coated with varnish, substantially in the manner and for the purpose set forth.

ALLEN H. BEHR.
